[57] ABSTRACT

A bank for collecting and safe keeping of coins or currency formed of two hemispherical members whose annular marginal edges are arranged to form a continuous annular gap therebetween when the bank is in the assembled and locked position. Access to the locking means is gained through the annular gap, any portion of which may be employed for inserting coins or even paper currency. Continuous lip means along the adjacent edges serve to prevent the currency from being removed.

1
BANK

The present invention relates to banks and more particularly to a novel, attractive and yet highly simplified structure for the collection and safe-keeping of currency while providing an aesthetically appealing and, in fact, somewhat deceptive structure as regards the nature of its primary function.

BACKGROUND OF THE INVENTION

There exists a wide variety of bank structures adapted for the collection and retention of currency and most particularly coins. Conventional banks are usually provided with a slot for insertion of currency and a panel or portion thereof containing a lock which, when operated to the unlocked position, permits removal or pivotal opening of the panel portion to gain access to the interior contents of the bank. Present day banks are also typically constructed in such a manner that the nature of their use is quite evident from their outward appearance.

BRIEF DESCRIPTION OF THE INVENTION AND OBJECTS

A major objective of the present invention is to provide a bank structure which does not give the outer appearance of being a bank, which is simple in design and thereby provides a device suitable for collecting and retaining coins and even paper currency with a capability equivalent to that of conventional banks, while at the same time providing an interesting and attractive "conversation piece."

The present invention is characterized by being comprised of a pair of hemispherical-shaped shell members which may be assembled to cooperatively form a hollow spherical shaped shell through suitable joining means. The hemispherical shaped halves, when assembled, have their marginal edges arranged at spaced intervals so as to define a continuous annular shaped opening suitable for receiving coins and even paper currency. The marginal edges of the hemispherical housing halves are provided with confronting surfaces of a width sufficient to prevent coins from being removed from the bank after having been inserted therein.

The outer appearance of the bank structure is such as to completely conceal the fact that any locking means is provided or for that matter that the bank may even be opened. In actuality, the locking means is comprised of telescoping interlocking or cooperating male and female members which interfit with one another. At least one of the members is provided with a set screw which is manipulated by an elongated "key," preferably an Allen type wrench, which is inserted through the same gap through which coins are inserted in the bank. The smooth lines and simplicity of the bank are such as to provide an interesting "conversation piece" whose identity, i.e., the fact that it is in actuality a bank, is not evident from the superficial appearance thereof.

BRIEF DESCRIPTION OF THE FIGURES

The above as well as other objects of the present invention will become apparent when reading the accompanying description and drawings in which:

2

FIG. 1a is an elevational view showing a bank designed in accordance with the principles of the present invention;

FIG. 1b shows a top view of the assembly of FIG. 1a;

FIG. 1c shows a plan view of a "key" employed for locking and/or opening the bank assembly of FIGS. 1a and 1b;

FIG. 1d shows an end view of the "key" of FIG. 1c;

FIG. 2a shows a side view of another preferred embodiment of the present invention;

FIG. 2b shows a sectional view of the embodiment of FIG. 2a;

FIG. 2c shows the joining means assembly employed in the embodiment of FIG. 2b in greater detail; and

FIG. 3 shows a sectional view of a lip portion of the embodiment of FIG. 1a, useful in describing one novel feature of the present invention.

DETAILED DESCRIPTION OF THE FIGURES

FIG. 1a and 1b show a bank 10 designed in accordance with the principles of the present invention and which is comprised of two hemispherical-shaped hollow shells 11 and 12 each provided with continuous annular shaped inwardly turned lips 11a and 12a respectively, whose function will become more evident and will be set forth in detail hereinbelow. Each of the shells is provided with an elongated projection 13 and 14 respectively secured to the inner surfaces of the shells so as to lie substantially along the spherical axis represented by phantom line 15. Securement may be provided through welding, for example.

Members 13 and 14 are preferably cylindrical in shape and are provided with male and female joining portions respectively, member 13 being provided with a cylindrical projection 13a of reduced diameter relative to portion 13; a member 14 being provided with a free end portion 14a of enlarged diameter. Cylindrical portion 14a is provided with an opening of a first diameter 16 which communicates with an opening 17 of reduced diameter, a portion of which extends into member 14. The bank, when fully assembled, is shown best in FIG. 1a wherein the reduced diameter portion 13a extends into opening 17 and a small portion of cylindrical member 13 extends into opening 16 so that its shoulder 14b abuts against the shoulder 16a between opening portions 16 and 17.

Member 14a is provided with a tapped opening 18 arranged substantially perpendicular to phantom line 15 and is adapted to receive and threadedly engage elongated threaded member 19. As can best be seen in FIG. 1a, a portion of projection 13a is provided with an annular groove 13b of reduced diameter which, when members 13 and 14 are interfitted in the manner shown in FIG. 1a, is positioned immediately adjacent the left hand end 19a of threaded "set screw" member 19.

The head of threaded member 19 is provided with a diamond-shaped opening 19b for receiving one end of a "key" 20 shown in FIG. 1c which is conventionally referred to as an "Allen" wrench. The Allen wrench typically has a cross-sectional configuration as shown in FIG. 1d which is diamond-shaped so as to conform to a similar shaped opening 19b provided in set screw 19. It should further be understood that the cross-sectional configuration of "key" 20 may be square shaped, pen-

tagonal, hexagonal and so forth with the opening 19b having a conforming configuration.

In order to disassemble the bank, either end or arm 20a or 20b of "key" 20 may be inserted into the opening 21 formed between the hemispherical halves 11 and 12 so as to be telescopingly received within opening 19b. By twisting or rotating "key" 20 in the appropriate direction, the end 19a of elongated member 19 is disengaged from the annular shaped groove 13b permitting the shell halves to be pulled apart. Assembly is performed in a similar manner wherein the two shell halves are aligned and projection 13a is inserted into opening 17 until shoulders 14b and 16a abut one another. Thereafter "key" 20 is inserted into gap 21 and into the conforming opening 19b in member 19 after which "key" 20 is rotated or twisted in the appropriate direction to cause end 19a to engage annular shaped groove 13b and thereby lock the shell halves 11 and 12 to one another.

Since the gap 21 is continuous and extends around the entire region defined by the marginal portions of shells 11 and 12, coins may be inserted into the bank at any point or location therealong. In addition thereto, paper currency may even be inserted into the bank due to the lengthy perimeter of the bank. In one preferred embodiment the bank has a diameter of approximately 4 inches so that the circumference of gap G is of the order of 12-1/2 inches which is clearly sufficient to receive paper currency if desired. As can be seen, the bank is provided with no stand or support whatsoever and is free to assume any position upon a flat surface. As a practical matter, once coins and/or paper currency are inserted therein, they will accumulate in a particular locale and thereby serve as a means for preventing the bank from freely rolling upon a flat surface.

The manner in which the coins and/or paper currency are retained within the bank can best be understood from a consideration of FIG. 3 wherein the inwardly turned lips 11a and 12a are shown in detailed fashion.

The length of inwardly turned flanges 11a and 12a is sufficient to prevent coins from being removed from the bank regardless of what angular position or orientation the bank has held. For example, let it be assumed that the bank is picked up and held so that the gap 21 shown in FIG. 1a is aligned so as to be co-planar with an imaginary vertical axis, hence the alignment shown in FIG. 3. Coins contained within the bank as represented by the dotted line outline C must be aligned so as to be substantially completely parallel with the planes of inwardly turned flanges 11a and 12a in order to move through the gap in the direction shown by arrow 22. As a practical matter, regardless of how much or how long or how vigorously the bank may be shaken, coins will assume an orientation as shown by the dotted line outline C' which is other than parallel in alignment with inwardly turned flanges 11a and 12a so that the coin (or coins) will be prohibited from passing through the annular gap 21 and hence will be prohibited from being removed from the bank.

FIGS. 2a through 2c show still another embodiment of the present invention. From a materials view point, the structure of FIGS. 1a and 1b is formed of a metallic material, such as for example stainless steel. The material employed in constructing the bank of FIGS. 2a through 2c is a plastic material. The embodiment 30 of

FIGS. 2a through 2c is comprised of hollow hemispherical shells 31 and 32 which are molded or otherwise machined so as to be provided with a pair of hollow cylindrical shaped projections 33 and 34 respectively, each of which are integrally joined to the interior surfaces of shells 31 and 32 along the imaginary axis 35 as shown best in FIG. 2b. The manner in which the two sections are joined is by means of a joining assembly 36 shown best in FIGS. 2b and 2c which is comprised of male and female members 37 and 38, respectively. Male member 37 is provided with a connecting portion 37a having a plurality of truncated conical shaped portions 37b which are adapted to be force fitted into the hollow opening 33a provided in tubular projection 33. The lower end of member 37 is provided with a cylindrical shaped flange 37c which tapers to form a section 37d of lesser diameter than both flange 37c and the conical truncated portion 37b. Projecting portion 37e is provided with an annular shaped shallow groove 37e which functions in a manner to be more fully described. Female member 38 is provided with a lower portion 38a having a plurality of truncated conical shaped sections 38b similar to the sections 37b of male member 37. The truncated conical section 38b forming portion 38a of the female member 38 is adapted to be force fitted within the hollow interior 34a of tubular projection 34 forming an integral part of shell 32. Section 38a is integrally joined to a portion 38c having a central opening 38d adapted to receive the portion 37d of member 37. Member 38c is preferably cylindrical in shape and has an annular flat upper surface 38e which engages the shoulder 37f of cylindrical shaped flange 37c when the parts are properly interfitted.

Member 38c has a cylindrical shaped projection 38g integrally joined to section 38c and provided with an opening 38h which is aligned with an opening 38j in portion 38c. These portions are both threaded as shown at 38k to receive an elongated threaded member (not shown for purposes of simplicity) which is substantially identical in nature to the member 19 shown for example in FIG. 1b. The manner of assembly is as follows:

Members 37 and 38 are joined to their associated hollow tubular projections 33 and 34 by force fitting their portions 37a and 38a into the interior of the hollow tubular shaped projections 33 and 34 in a manner shown best in FIG. 2b. Assembly of the two shell halves is obtained by aligning members 37 and 38 so that they lie along the same longitudinal axis designated by dotted line 35 shown in FIGS. 2b and 2c. The male member 37d is then pressed into female member 38c until the shoulder 37f abuts against surface 38d. In this position the shallow annular shaped groove 37e will be aligned with the co-aligned openings 38h and 38j. By inserting a key into threaded member 19 in the same manner as described hereinabove in connection with FIGS. 1b and 1c, the key must then be twisted or rotated until the end of the threaded member inserted into and threadedly engaging threaded openings 38h and 38j is seated in shallow groove 38e thereby preventing the two halves from being separated. The force fitting of members 37 and 38 into tubular shaped projections 33 and 34 is sufficient to prevent their removal due to the nature of the truncated conical shaped tapering portions 37a and 38a respectively.

In order to open the bank, the key member is inserted into the cooperating opening of appropriate conform-

ing shape in member 19 (see FIG. 1b) and the key is then twisted or rotated until the end of the member inserted into the shallow groove is separated herefrom to enable the two shells to be separated from one another.

Whereas member 19 has been shown as being elongated, it should be noted that member 19 can be made much shorter so that its end 19b could be arranged for example, to lie at the position 19b' shown in FIG. 1b. In order to open or close the bank assembly utilizing such a short threaded member, the arm 20b of "key" 20 may be that portion of the key inserted into gap 21 for the purpose of being inserted into opening 19b in order to loosen member 19b and thereby open the bank. Conversely, the same arrangement may be employed for closing and locking the bank.

The components 31 and 32 of the embodiment shown in FIGS. 2a and 2b may separately be formed through a molding operation. Since it is extremely difficult to mold a lip of the type shown in 11a and 12a in the bank formed of a metallic material, the marginal portion of shells 31 and 32 are molded or otherwise formed so as to have increased thickness T relative to the thickness T' of the remaining portion of the shell as shown best in FIG. 2b. Thickness of the confronting marginal portions is chosen so as to be substantially commensurate with the length of the lip or flanges 11a and 12a showing the embodiments of FIGS. 1a and 1b

Whereas the preferred embodiments teach a spherical shaped bank it should be understood that other shapes are possible for use without departing from the significant features of this invention. For example, the shell halves can collectively form other regular or even irregular geometric figures such as polyhedrons and the like. Also, each shell need not form exactly one-half of the final shape so that the shells may collectively form one-third and two-thirds of a sphere for example, so long as the insert gap and inwardly turned flanges and the joining and locking means are employed.

Although the present invention has been described in connection with a preferred embodiment thereof, many variations and modifications will now become apparent to those skilled in the art. It is preferred, therefore, that the present invention be limited not by the specific disclosure herein, but only by the appended claims.

We claim:

1. Apparatus for receiving and collecting currency and coins comprising:
first and second shells having concave interior surfaces;
joining means having first and second ends secured to said concave interior surfaces of said first and second shells for joining said shells to form a substantially hollow housing cooperatively defined by said first and second shells;
each of said shells having a continuous marginal edge, said edges of said first and second shells being substantially uniformly spaced from one another when said shells are joined, thereby to define a substantially continuous and substantially uniform width annular gap therebetween;
each of said marginal edges having an edge surface of predetermined width, said edge surfaces confronting one another to define said gap therebetween; the widths of said edge surfaces and the

width of said gap being selected to cooperate to prevent currency and coins collected in said housing from being removed therefrom without disassembling said shells.

5 2. The apparatus of claim 1, wherein said joining means is further comprised of an intermediate section defined by first and second separable portions adapted to be coupled to one another;

10 locking means movably joined to one of said sections and adapted to abut the other of said sections when they coupled to one another for locking said sections to one another and thereby prevent said shells from being disassembled.

15 3. The apparatus of claim 2, wherein said locking means has a key receiving opening positioned so as to be in alignment with at least a portion of said gap;

20 key means having an operating handle and an actuating means extending therefrom, the free end of said actuating means being insertable through said gap and into said key receiving opening to respectively move said locking means into and out of engagement with said other of said sections for locking and opening said apparatus.

25 4. The apparatus of claim 3, wherein said key receiving opening and said key actuating means have conforming cross-sectional configurations.

25 5. The apparatus of claim 2, wherein one of said sections has a projecting portion and the other of said sections has an opening adapted to receive said projecting portion;

30 said locking means comprising a threaded member threadedly engaging a tapped aperture provided in said other section and communicating with said opening to enable one end of said threaded member to enter into said opening and abut said projecting portion when rotated in a first direction to lock the joined sections.

35 6. The apparatus of claim 1, wherein said edge surfaces are each comprised of inwardly turned flanges projecting toward the interior of said housing.

40 7. The apparatus of claim 5, wherein the length of said threaded member is such as to position the actuating opening a small spaced distance inwardly of said cooperating edge surfaces.

45 8. The apparatus of claim 1, wherein said first and second shells collectively define a three-dimensional geometric figure.

45 9. The apparatus of claim 8, wherein said geometric figure is a sphere.

50 10. The apparatus of claim 5, wherein said projecting portion has an annular groove spaced inwardly from its free end, said groove being aligned with said tapped aperture when said cooperating sections are joined so as to receive and be engaged by the adjacent end of said threaded member in the locked position and thereby prevent said sections from being separated.

55 11. The apparatus of claim 1, wherein said gap is of a width greater than the narrowest dimension of coin and currency to be placed in said housing and less than the long dimension of that coin and currency.

60 12. The apparatus of claim 1, wherein said gap and said marginal edges are continuous around the entirety of both said shells and said housing.

65 13. The apparatus of claim 1, wherein said width of said surfaces is a substantial portion of the long dimension of the coin and currency to be placed in said housing.

14. The apparatus of claim 13, wherein said edge surfaces are each comprised of inwardly turned flanges projecting toward the interior of said housing.

65 15. The apparatus of claim 14, wherein said gap and said marginal edges are continuous around the entirety of both said shells and said housing.
